W.H. MANNS.

BY *Munn & Co.*

ATTORNEYS

UNITED STATES PATENT OFFICE.

WALTER H. MANNS, OF CHICAGO, ILLINOIS.

MOTOR METER.

Application filed March 27, 1920. Serial No. 369,239.

To all whom it may concern:

Be it known that I, WALTER H. MANNS, a citizen of the United States, and a resident of Chicago, in the county of Cook and State of Illinois, have invented a new and useful Improvement in Motor Meters, of which the following is a full, clear, and exact description.

My invention relates to improvements in means for indicating the condition of an internal combustion engine, and it consists in the combinations, constructions, and arrangements herein described and claimed.

An object of my invention is to provide a novel form of a device for indicating the condition of an internal combustion engine which can be quickly and readily attached to the cooling apparatus of the engine.

A further object of my invention is to provide a device of the type described that is particularly adapted to be attached to the radiator for a liquid-cooled internal combustion engine and in which means is provided to instantly indicate changes in the temperature of the cooling fluid circulating through the radiator, whereby the condition of the engine is disclosed.

A further object of my invention is to provide a device of the type described that is attractive in appearance, relatively simple in construction and operation, not liable to get out of order easily, and thoroughly practical commercially.

Other objects and advantages will appear in the following specification, and the novel features of the invention will be particularly pointed out in the appended claims.

My invention is illustrated in the accompanying drawings, forming part of this application, in which—

Fig. 1 is a central vertical section through the device, a portion being shown in side elevation.

Fig. 2 is a plan view of the device.

Fig. 3 is a section along the line 3—3 of Fig. 1.

In carrying out my invention, I make use of a radiator 1 for a liquid-cooled internal combustion engine. A radiator cap 1^a is threaded at 2 for screwing on the filler spout of the radiator. The radiator cap 1^a is

formed with a central threaded opening 3 in which an exteriorly threaded lower end 4 of a sleeve or nipple 5 is screwed. The sleeve or nipple 5 is held in position by a nut 6 which is placed on the lower end thereof. The sleeve or nipple 5 is also threaded interiorly at 7 to receive an enlarged threaded portion 8 of a tubular casing 9. It will be noted that the enlarged portion 8 is formed intermediate the length of the tubular casing 9 which has its lower portion depending within the radiator 1. The lower portion of the tubular casing 9 is closed by an end portion 10.

A lower base 12, which conforms in shape substantially to that of a segment of a sphere provided with arcuately extending diametrically opposed lugs 13, has a central opening 14 enlarged and threaded at 15 for screwing on a threaded upper end 11 of the sleeve or nipple 5. A circular upper base 16, having a beveled circumferential edge, is formed with a threaded central socket 17 in its lower surface and the threaded upper end 18 of the tubular casing 9 is received therein. A card 19 having a temperature scale 20 delineated thereon, as shown in Fig. 2, is disposed upon the upper surface of the upper base 16.

A rod 21 is inserted within the tubular casing 9 and extends the length thereof. The rod 21 has an extension 22 passed through registering central openings in the upper base 16 and the card 19 and then bent laterally to form an indicator arm 23. It will be noted that a rotation of the rod 21 will cause the indicator arm 23 to move arcuately around the card 19.

A housing 24, which is that portion of a sphere which will in cooperation with the lower circular base 12 form a complete sphere, is arranged to enclose the upper base 16, as clearly shown in Fig. 1. The housing 24 is formed of a transparent material, such as glass, the portion 25 located above the upper base 16 being clear so that the temperature scale 20 upon the card 19 is plainly visible. It will be understood that in order to effect the arrangement of the lower base 12 and the housing 24 shown in Fig. 1, the lower base 12 is in-

serted within the housing 24 and is then drawn downwardly into position when the threaded upper end 11 of the nipple 5 is screwed into the threaded opening 15. The 5 inner arcuate surface of the sphere 24, between the upper base 16 and the lower base 12, is coated with quick-silver 26, or a like substance to cause the corresponding outer surface of the housing 24 to act as a mirror.

10 A quantity of asbestos packing 27, or any other substance which is a non-conductor of heat, is disposed about the upper portion of the tubular casing 9.

It will be noted that the rod 21 extends 15 through the center of a lower disk 29 which can be moved vertically therealong. A coil spring 28 is disposed between the lower disk 29 and the bottom end 10 of the tubular casing 9, being secured at its upper end to the 20 disk 29 and at its lower end to the bottom wall 10. The space within the coil spring 28 is filled with mercury, alcohol, ether, or a like temperature responsive element. A spiral member 30 has its lower end rigidly 25 secured to the upper surface of the disk 29 and has its upper end inserted within an opening 31 in an upper disk 32 through which the rod 21 extends. The disk 32 is rigidly secured to the rod 21 and rotation of 30 the former will rotate the rod 21. The lower disk 29 is formed with diametrically opposed lugs 33 adapted to be received within the vertical grooves 34 which are formed in the inner wall of the tubular casing 9. It 35 will therefore be noted that the movement of the disk 29 is limited to a vertical reciprocation.

From the foregoing description of the various parts of the device, the operation 40 thereof may be readily understood. The radiator cap 1^a is placed upon the filler spout in an ordinary manner, thereby causing the lower end of the tubular casing 9, which contains the coil spring 28 and the 45 temperature responsive element, to depend within the radiator 1. The indicator arm 23 is positioned to indicate the temperature within the radiator by pointing to graduations of the temperature scale 20, which will 50 register temperature in degrees, Fahrenheit, or centigrade, as desired. The temperature responsive element, such as mercury, or the like, contained within the coil spring 28 will be affected by a change of temperature 55 within the radiator 1 and will expand or contract as the temperature increases or decreases. When the temperature responsive element expands, the disk 29 is moved upwardly, thereby extending the spring 28. 60 When the temperature responsive element contracts, the action of the coil spring 28 returns the disk 29 toward initial position, or in other words, moves the disk 29 downwardly in the casing 9. Consequently the 65 disk 32 is rotated by the obvious action of

the spiral member 30; which is forced upwardly by the upward movement of the lower disk 29 and pulled downwardly by the lower disk 29 when the latter is moved downwardly by the coil spring 28. The 70 coils of the coil spring 28 move freely vertically in the casing 9.

Since the upper portion of the housing 24 is clear, and the scale 20 visible, the operator of the internal combustion engine will be instantaneously apprised of temperature changes occurring through the radiator. Since the condition of the cooling fluid circulating through the radiator is governed by the condition of the internal combustion engine, 75 the operator will be at all time aware of the condition of his engine and will be notified when any abnormal condition exists, which, if continued, is likely to result in damage to the engine or the parts associated therewith. 80 The device is ornamental in appearance and enhances the appearance of the radiator to which applied. When the device is applied to the radiator of an automobile which is in motion, objects passed will be reflected 85 by the portion of the housing 24 that is arranged to act as a mirror.

I claim:

1. A device of the character described comprising a cap, a glass sphere secured to 95 said cap, a plate disposed adjacent to the top of said sphere and having a central opening therein and series of markings thereon, a tubular member secured to said disc and projecting below said cap, said tube 100 having its lower end closed and having a recess in the inner surface thereof, a rod pivotally disposed in said opening and said recess and having its upper end bent at right angles thereto, a disc, having an opening therein, carried by said rod a second disc slidably disposed on said rod and carrying a spiral member which projects through the opening of said first named disc, a spring secured to 105 said second named disc and to said tube, and a temperature responsive fluid carried by said tube and being disposed below said second named disc.

2. A device of the type described comprising a cap, a tube carried by said cap, and having its lower end closed, a plate carried by the upper end of said tube and having a central opening therein and series of markings thereon, an indicating rod journaled in the closed end of said tube and pivotally 110 disposed in said opening, a disc having an opening thereon rigidly secured to said rod, a second disc slidably mounted on said rod and carrying a spiral member which extends through the opening of said first named disc, and a temperature responsive fluid carried by said tube and being disposed below said second named disc.

3. A device of the character described comprising a cap, a tube carried by said cap, 115

said tube being closed at its lower end, a rod and having an opening therein, a second plate carried by the upper end of said tube, said plate having a central opening therein and a series of markings thereon, an indicating rod journalled in the lower end of said tube and being pivotally disposed in said opening, a disc rigidly secured to said

disc slidably disposed on said rod and having a spiral member which extends through the opening in said first named disc, and means for moving said second named disc toward and away from said first named disc.
